UNITED STATES PATENT OFFICE.

ENOCH M. FREDERICKS, OF CHICAGO, ILLINOIS, ASSIGNOR TO JOY TOOTH COMPANY, OF CHICAGO, ILLINOIS, A CORPORATION OF ILLINOIS.

ARTIFICIAL-TOOTH CROWN AND SECURING MEANS THEREFOR.

1,418,070.

Specification of Letters Patent. Patented May 30, 1922.

Application filed November 10, 1919. Serial No. 336,905.

To all whom it may concern:

Be it known that I, ENOCH M. FREDERICKS, a citizen of the United States, residing at Chicago, in the county of Cook and State of Illinois, have invented certain new and useful Improvements in an Artificial-Tooth Crown and Securing Means Therefor, of which the following is a specification.

My present invention relates to improvements in artificial tooth crowns and means for securing the same of a type somewhat similar to that disclosed in Letters Patent of the United States, Number 900,363, issued to me on October 6, 1908, and has for one of its objects to greatly improve the construction and efficiency of tooth crowns made according to my aforesaid Letters Patent, and to economize in the amount of certain material used in the construction of the tooth crown and securing means set forth in said Letters Patent, without diminishing its strength or efficiency, and without an increase in the amount of labor and time expended in fitting the crown to or mounting it upon the root of the tooth.

Further objects and advantages of the invention are similar to those set forth in my aforesaid Letters Patent and are as follows:

To provide an artificial tooth crown, more especially for the molar or bicuspid type, which shall be of such construction or shape that it may be readily prepared to accurately fit the backing and solder-base, and in some instances, the exposed end of the natural root with a minimum of grinding or cutting away of parts.

Another object is to provide simple and efficient means for securing the crown firmly in place on the backing and solder-base and in some cases for securing the crown directly and firmly to the root, and in either case, in such a manner that in the event of breakage of the crown, it will be unnecessary to remove the crown-post in order to place a new crown thereon.

A further object is to provide means whereby the soldering necessary in securing the crown and parts together may be accomplished without injury to or discoloration of the crown.

Other objects and advantages of the invention will be disclosed in the subjoined description and explanation.

The invention consists in certain peculiarities of the construction, novel arrange-

ment, combination and operation of the various parts thereof, as will be hereinafter more fully set forth and specifically claimed, and in order to enable others skilled in the art to which my invention pertains to make and use the same, I will now proceed to describe it, referring to the accompanying drawing, which serves to illustrate an embodiment of my present improvements, and in which drawing the views are greatly exaggerated.

Fig. 1 of the drawing is a sectional view of a tooth crown provided with fastening means arranged and constructed according to my present invention, showing it secured to the backing and solder-base and the latter to a portion of the natural root of a molar tooth.

Fig. 2 is a longitudinal sectional view of a portion of the crown-post or pin.

Fig. 3 is a cross-sectional view thereof taken on line 3—3 of Fig. 2 looking in the direction indicated by the arrows.

Fig. 4 is a detached plan view of the metallic band used in the cavity of the tooth crown for a bearing or support for the crown-post.

Fig. 5 is a transverse sectional view thereof taken on line 5—5 of Fig. 4 looking in the direction indicated by the arrows.

Fig. 6 is a detached perspective view of a form of a tooth crown similar to that shown in Fig. 1 illustrating the metallic band located in the upper end of the cavity of said crown, and illustrating the same as applied to a front tooth, and

Fig. 7 is a similar view of a tooth crown showing a modification in its construction.

Like numerals of reference refer to corresponding parts throughout the different views of the drawing.

The reference numeral 7 designates a portion of the root of a natural tooth, in the cavity of which is secured by means of cement 8 or otherwise, a post 9, which I will term the solder-post and is used in connection with the gold backing 10 secured on the exposed end of the root to secure the solder-base 11 to the root.

As shown in Fig. 1 of the drawing, the solder-post 9 projects through the backing 10 and into the solder-base 11 and thus firmly secures said parts together as well as to the root.

The numeral 12 designates, as a whole, the artificial crown which may be made of any

suitable shape and size in accordance with the position in which it is to be placed, and is preferably formed of porcelain, but may be made of other suitable material. When 5 made of the molar or bicuspid type, the crown 12 has extending therefrom a shank or flange 14, which in cross-section is of very much less size or area than the crown portion 13, so that in fitting the crown to the 10 solder-base, or when desired, to the root, it will be necessary to cut away or grind off the shank or flange only to the desired point, thus saving much time and labor.

Molded in the usual manner, or in the preferred way, in the crown 12 is a supporting or bearing band 15 which is preferably made of platinum, but may be of any other refractory metal. As shown, this band is substantially circular in shape but is provided 15 with diametrically opposed and outwardly extended bosses or protuberances 16 produced by stamping or otherwise forming in the inner surface of that portion of the band 15 where the bosses 16 are located, vertically 20 disposed grooves 17 which grooves extend through the upper and lower edges of the band, as will be clearly understood by reference to Figs. 1, 4 and 5 of the drawing. This band is located in the upper or outer end 25 of the cavity 18^a of the tooth crown which cavity is tapered or enlarged towards its bottom.

While I have shown the band 15 provided with a pair of opposed bosses 16 located 30 diametrically opposite each other and each equipped on its inner surface with a groove 17, yet I desire it to be understood that the band may be provided with one or more of the grooves and the resultant bosses or protuberances and that they may be arranged 35 diametrically opposite each other or otherwise. Located within the band 15 is one end of the crown securing post 18 the opposite end portion of which is adapted to be 40 inserted and secured in any desired manner in the solder-base. The portion of that part of the post 18 located within the tooth crown 12 is formed with a tapered part 19 corresponding with the tapered cavity 18^a of the 45 tooth crown yet smaller in size so as to leave a space surrounding the same between it and the tapered wall of the cavity 18^a as will be readily understood by reference to Fig. 1 of the drawing, in which view it will be observed 50 that the tapered part 19 of said post has its larger portion at its free end to rest on or to lie in close proximity to the base of the cavity in the crown. To form this tapered portion 19 the post 18 is reduced thus forming 55 an annular shoulder 20 at the smaller end of the tapered part 19, which shoulder as shown in Fig. 1 is located some distance from the front outer or upper edge of the band 15 and within the same. The base or 60 free end of the tapered part 19 is preferably

of the same size as that of the post 18 at the outer end or edge of the band 15, that is to say, said base as well as the post, is of a sufficient size to pass through the band, yet so that the body portion of the post, when in 70 position within the band, will contact therewith, thereby forming a bearing or support at such point.

The post 18 is provided with one or more grooves 21 which extend longitudinally 75 from the shoulder 20 to a point outwardly from the outer edge or end of the band, as will be readily understood by reference to Fig. 1 of the drawing, and said grooves as well as the grooves 17 in the interior of the 80 band 15, are for the purpose of permitting air to pass out when the post is inserted in the band and cavity 18^a, and also for the purpose of permitting the cement 22 to enter 85 said grooves, and thereby form locks or means for more securely holding the post in position.

The grooves 21 in the post 18 correspond in number and location thereon so that when the post is inserted in the band 15 and 90 cavity 18^a the grooves 17 in the band will register with the grooves 21 in the post.

So far, the construction of the parts in the present application are substantially the same as those shown and described in my above named Letters Patent, except, that in the present instance or construction, I employ a narrow band 15 instead of a tapered tubular shell used in the patented construction. As the band and shell are by 100 preference made of platinum which is quite expensive, it is apparent that by employing the band instead of the shell, considerable saving in said material is attained, yet a very secure and effective support or bearing 105 for the crown-post is provided.

In the construction of the present application, the tooth crown 12 is provided in its upper portion or that part thereof adjacent to the solder-base 11 when the crown is 110 mounted on the crown-post with one or more grooves 23 which will lead from the upper ends of the grooves 17 in the band 15 to the front and rear surfaces of the tooth crown, as is clearly shown in Figs. 1 and 6 115 of the drawing. The inner ends of these grooves also communicate with the upper ends of the grooves 21 as shown, and will thus provide escapeways or passages for air and surplus cement, which will be forced 120 out of the cavity of the tooth crown when the same is fitted on the crown-post.

By reference to Figs. 1 and 6 it will be seen that one of the grooves 23 extends over the upper portion of the shank or flange 14 125 of the tooth crown while the other groove 23 extends in the opposite direction to the inner edge of the crown. It will be understood that the tooth crown may be provided with grooves 23 to correspond in number 130

and location to the grooves in the band 15 and the grooves in the crown-post 18 with which the grooves of the tooth crown will register.

5 Instead of locating the grooves 23 in the tooth crown so as to extend forwardly and rearwardly thereof as shown in Figs. 1 and 6 of the drawing, they may be located so as to extend laterally of the crown as is shown 10 in the modified construction illustrated in Fig. 7 of the drawing, when it will be understood that the same connections of the grooves 23 with those of the band and post and above described will be attained and for 15 the same purpose.

A further novel feature of my present invention is the formation on the upper portion of the tooth crown with a substantially annular reduced portion 24 and a similar shoulder 25 below the same. By this construction, it is obvious that when the crowns 12 are placed side by side and it is desired to unite them together by a suitable backing and solder that the upwardly rounded reduced portions 24 of the crowns will be located at a sufficient distance apart to permit of sufficient amount of solder to be located on the backing which lies on the shoulder 25 as well as the portion 24 and between 25 said rounded portions to greatly strengthen 30 said rounded portions to greatly strengthen the uniting support or backing for the crowns without interfering with the proper fitting of the crowns in their proper places.

While I have shown the post 18 provided 35 with grooves 21 and while I prefer to use a post provided with one or more of such grooves, yet it is obvious that the same may be omitted from the post, when it is apparent that the grooves 23 in the tooth crown 40 will communicate with the grooves 17 in the band 15 and thus permit the escapement of air and surplus cement from the cavity out through the surfaces of the crown. It is also apparent that a post provided with 45 one or more grooves may be employed and the grooves 17 omitted from the band, in which case the inner ends of the grooves 23 in the tooth crown will communicate with the cavity 18^a through the grooves of the 50 post and thus provide escape-ways to the outer surfaces of the tooth crown.

In carrying my invention into practice, it will be understood that the root 7, is provided with a suitable opening for the reception 55 and retention of the solder-post 9, and a sufficient quantity of cement 8, to secure said post in position in said opening at the time desired. The solder post 9, and backing 10, are secured together as a unit, so that 60 the said post can be readily inserted in the opening in the root 7 therefor, and so that the backing 10, can be easily fitted on the exposed end of the root.

The backing 26 is burnished on the crown 65 12 and the crown post 18 is extended through

a suitable opening in the backing 26, into the cavity 18^a of the crown and said backing and post and are soldered together. The parts are now ready to be fitted, and this is accomplished by placing the post 9 in the 70 opening of the root so that the backing 10 will rest on the exposed end of the root. The crown 12, backing 26 and post 18 are adjusted in place in the mouth, with wax between the bases 10 and 26. Then the post 9, backing 10, post 18, backing 26, (with wax between it and the backing 10), the crown 12 in place on the backing 26 is removed from the mouth as a unit. The crown is then removed, and the said united parts are invested 80 and the wax removed and supplanted with solder, forming the base 11. That portion of the backing 26 located in the grooves 23 of the crown is removed by any suitable instrument so as to leave said grooves open. 85 The backing 26 carrying the post 13 is then soldered to the solder-base or root covering, when a quantity of cement is placed in said cavity, and the crown is then placed on the backing 26 in which operation the tapered 90 portion of the post will enter the cavity of the crown, thus causing the cement to surround the tapered portion of the post, where it will become hardened or set, and will firmly hold the crown in position on the 95 post. In the act of placing the crown on its post, it is apparent that the grooves 17 in the band and the grooves 21 in the post, when both are used or when either is used, will 100 permit the air and surplus cement to escape from the cavity of the crown and to pass out through the passageways 23 and thus allow the post to be properly fitted therein. These grooves will also receive a portion of the cement, and after it becomes hardened, it 105 will serve to prevent the crown turning on the post, and otherwise more securely hold it in position. As the band is provided with one or more of the protuberances 16 on its periphery, it is manifest that the same will 110 be imbedded in the material of which the crown is made and in which it has been molded, thus preventing any possibility of rotary movement of the band with respect to its crown.

Having thus fully described my invention, what I claim as new and desire to secure by Letters Patent is—

1. As an article of manufacture, an artificial tooth crown having a post receiving 120 cavity therein and provided with at least one groove in its surface adjacent to the outer end of said cavity, said groove leading from the cavity to the outer surface of the crown, and a metallic band located in the outer extremity of the cavity.

2. As an improved article of manufacture, an artificial tooth crown having a post receiving inwardly enlarged tapered cavity 125 therein and provided with at least one 130

groove in its surface adjacent to the outer end of said cavity, said groove leading from the cavity to the outer surface of the crown, and a metallic band located in said cavity and having in its inner surface one or more grooves to register with the groove or grooves of the crown.

3. The combination with a tooth crown having a post receiving inwardly enlarged tapered cavity therein and provided with at least one groove in its surface adjacent to the outer end of said cavity, said groove leading from the cavity to the outer surface of the crown, the crown also having a reduced and substantially annular portion and a substantially annular shoulder around the outer extremity of said cavity, and a metallic band located in said cavity and having in its inner surface one or more grooves to register with the groove or grooves of the crown.

4. The combination with a tooth crown having a post receiving inwardly enlarged tapered cavity therein and provided with one or more grooves in its surface adjacent to the outer end of said cavity, said groove or grooves leading from the cavity to the outer surface of the crown, the crown also having a reduced and substantially annular portion and a substantially annular shoulder around the outer extremity of said cavity through which said grooves are extended, a metallic band located in the outer extremity of the cavity against the walls thereof and having in its inner surface one or more longitudinally extending grooves registering

with the grooves of the crown, a securing post located at one of its ends in the band and having a portion within the cavity tapered from its inner end towards the inner end of the band.

5. As an improved article of manufacture, a tooth crown having a post receiving cavity therein and provided with one or more grooves in its surface adjacent to the end of said cavity, said groove or grooves leading from the cavity to the outer surface of the crown, the crown also having a reduced and substantially annular portion and a substantially annular shoulder around the outer extremity of said cavity through which said grooves are extended, and a metallic band located in the outer extremity of the cavity against the walls thereof.

6. In a device of the class described, a base, a tooth crown adapted to fit snugly upon said base, the abutting faces of said base and crown having grooves registering with each other and disposed substantially from side to side of the crown, and a locking element in the said grooves.

7. In a device of the class described, a pair of closely fitting tooth forming elements, one of said elements having a recess therein, a post on the other element adapted to fit in said recess, the abutting faces of said elements having grooves therein extending at their inner ends to and communicating with the said recess, and the said recess and grooves adapted to contain a cement.

ENOCH M. FREDERICKS.
